UNITED STATES PATENT OFFICE.

WARNER R. BUXTON, OF SPRINGFIELD, MASSACHUSETTS.

TOBACCO-POUCH.

1,262,634.

Specification of Letters Patent. Patented Apr. 16, 1918.

Application filed July 5, 1917. Serial No. 178,776.

To all whom it may concern:

Be it known that I, WARNER R. BUXTON, a citizen of the United States of America, residing at Springfield, in the county of 5 Hampden and State of Massachusetts, have invented certain new and useful Improvements in Tobacco-Pouches, of which the following is a specification.

This invention relates to improvements in 10 tobacco pouches.

An object of the invention is to provide a pouch of convenient shape and of substantially flat form, wherein the usual relatively large opening for filling the pouch 15 and a closure flap for the opening is provided, together with another opening relatively small in comparison with the first opening and a foldable closure flap for the second opening, the last named flap being 20 adapted to be extended from the pouch to form a discharge trough for the second opening and being characterized in that it is of a size and shape adapted for insertion in the bowl of a pipe to conveniently fill 25 the latter.

Other objects and advantages will appear in the following description and in the appended claims.

The invention, in an embodiment at present preferred, is shown for illustrative purposes in the accompanying drawings; in which—

Figure 1 is a front elevational view showing the closed pouch;

Fig. 2 is a similar view showing the discharge opening with its closure flap in extended trough forming position, and

Fig. 3 is a side elevational view of the pouch illustrating its use in the filling of a 40 tobacco pipe.

Referring to these drawings, the pouch may be conveniently made up from two pieces 1 and 2 of suitable material, preferably leather or the like. The front forming 45 piece 1 is, in the embodiment illustrated, of substantially semi-oval shape, and the back forming member 2 is of similar size and shape except that it is provided in addition with integrally formed upper and lower flap 50 forming extensions 3 and 4, respectively. The two halves 1 and 2 of the pouch are arranged face to face and suitably secured, one to another, as by stitches 5, along their coincident marginal portions, 55 which includes all of the curved marginal

portion except for a relatively small and centrally arranged portion 6. There are thus, upper and lower non-coincident marginal portions of members 1 and 2 which are unsecured whereby upper and lower 60 pouch openings are provided. The upper opening is relatively large and, as illustrated, may extend across the full width of the pouch, while the lower is very small in comparison with the upper opening. The 65 upper and lower pouch openings may be separately closed, as shown in Fig. 1, by the flaps 3 and 4 which may be held in pouch closing position by snap fasteners 7 and 8, respectively, or any other suitable means. 70

In use, the pouch is filled by means of the large upper opening in the usual manner, but in removing tobacco from the pouch the relatively small opening is used in conjunction with the flap 4 in an advantageous 75 manner as will be described. The lower opening of the pouch is, as has been stated, small and the width of flap 4 is only slightly larger than the length of the opening, as indicated in Fig. 2. The size of the open- 80 ing and width of the flap is comparable to the diameter of the ordinary pipe bowl, and these dimensions are of importance since it is particularly an object to have the flap capable of insertion in the bowl of the pipe. 85 Thus, when fastener 8 is released, flap 4 may be moved into the position shown in Fig. 2, wherein it forms a continuation or extension of the back member 2 beyond the bottom of 90 the pouch.

The flap 4, when positioned as in Fig. 2, will readily assume a desirable trough forming shape, when the side edges of the pouch are squeezed together. It is to be noted that no special construction of the flap is 95 necessary to obtain this result, but on the contrary the flap is so arranged with respect to other parts of the pouch that there is a natural tendency for it to assume a curved or concave cross sectional shape. Thus, the 100 contents of the pouch cause the walls 1 and 2 thereof to bulge outwardly intermediate the stitched edges and the natural bulging obtained in a pouch of this character is made use of to advantage in the present invention since the flap 4, being an integral part of the back wall 2, tends to assume a similar bulge so far as is permitted by the stitching 5. Thus, the flap 4 is not only of 105 the requisite size for insertion in a pipe 110

bowl, but it is also curved so that its cross sectional shape conforms approximately with the curvature of the bowl.

The flap, therefore, may lie substantially contiguous with a portion of the inner periphery of a pipe P, as shown in Fig. 3, in which position tobacco may be conveniently discharged into the pipe bowl. The flow of tobacco down the trough forming flap 4 10 may be controlled by tilting the pouch and also by the degree of pressure applied to the walls of the pouch. As the lower part of the bowl becomes nearly full, the pouch is tilted toward the horizontal to decrease the flow. 15 Any tobacco remaining in the trough may be readily returned to the pouch by tilting the lower end upwardly while still maintaining the pressure on the sides of the pouch. 20 The pouch, therefore, is particularly advantageous, not only on account of convenience in filling a tobacco pipe, but also on account of the arrangement, whereby the trough forming flap is adapted for insertion 25 in the bowl of the pipe, by which arrangement the latter may be filled without loss or wastage of tobacco.

The invention has been described herein for illustrative purposes, but the scope of 30 the invention is defined by the appended claims rather than by the foregoing description.

What I claim is—

1. A tobacco pouch of substantially flat

form, having front and rear walls of flexible material connected to form therebetween a container having a relatively large filling opening and a relatively small discharge opening, a separate closure flap for each opening, the flap for the discharge opening 40 being arranged for extension from the pouch and so constructed that, when extended, it may be inserted in the bowl of a tobacco pipe, the flap being arranged to bend into curved cross-sectional trough forming shape 45 when the walls of the pouch are squeezed together, whereby the trough may fit within and conform to the curvature of the pipe bowl for the purpose of conveniently filling the latter. 50

2. A tobacco pouch of substantially flat form having front and rear walls connected to form therebetween a relatively large and a relatively small opening, a closure flap for each opening comprising a portion on one 55 wall foldable over the other wall in overlapping relation, the flap for the small opening arranged when extended from the pouch to form a trough for its opening and adapted to be inserted in the bowl of a tobacco pipe, the last-named wall adjacent the small opening having an edge which curves from its central portion on each side toward the flap when in extended position and which is substantially tangential at its 60 central portion with the line of fold of said trough forming flap. 65

WARNER R. BUXTON.
